UNITED STATES PATENT OFFICE

JOHAN ANSHELM GRANSTEDT, OF SJALEVAD, SWEDEN

COOLING APPARATUS

Original application filed June 27, 1928, Serial No. 288,753, and in Sweden March 16, 1928. Divided and this application filed October 11, 1929. Serial No. 398,978.

This invention relates to water cooling systems for motor vehicles and has for its object to provide a radiator cap which may be used both as a filling tube for the radiator and as

5 a condenser to condense the steam generated in the radiator and pass the water of condensation back into the radiator.

The invention is characterized by the fact the said cap comprises a hollow ball or the 10 like having an opening surrounded by a threaded nipple adapted to be screwed into the threaded inlet hole of the radiator, a tube extending through said ball at right angles to the direction of said opening and projecting 15 at both ends outside said ball, one projecting end forming an intake funnel, whilst the other projecting end constitutes an outwardly threaded nipple of the same dimensions as the said first-mentioned nipple.

20 One embodiment of the invention is illustrated in the accompanying drawing which shows a vertical section of a radiator cap according to this invention.

With reference to the drawing the numeral 25 1 indicates a hollow ball having an opening at 2 surrounding by a projecting nipple 3 which is threaded outwardly so that it may be screwed into the threaded inlet hole of the radiator of a motor vehicle.

30 Extending through the ball 1 in a direction at right angles to the direction of the opening 2 is a tube 4 formed integral with the ball 1. The tube 3 projects at both of its ends beyond the periphery of the ball 1. One projecting 35 end of the tube is shaped as a funnel 5, whilst the other projecting end 6 of tube 4 is cylindrical in shape and threaded outwardly. The diameter of the threaded end 6 is equal to that of the nipple 3 so that the end 6 may also be 40 screwed into the inlet hole of the radiator.

With the nipple 3 in engagement with said inlet hole the ball 1 with its tube 4 operates as a condenser to condense the steam generated in the radiator and pass the water of condensation back into the radiator. The reason 45 for this operation is that atmospheric air is forced through the tube 4 during the running of the vehicle and to this end the funnel 5 should be directed forwardly.

50 After unscrewing of the nipple 3 from the

hole of the radiator and screwing the threaded end or nipple into said hole the tube 4 with its funnel 5 may be used in refilling the radiator with water.

It is to be noted that the tube 4 may, of course, be formed as a separate piece secured to the ball 1 in any suitable way.

What I claim is:

1. The herein described attachment for an automobile radiator, comprising a hollow body having an opening surrounded by a projecting threaded nipple to engage a threaded hole in the radiator, an open-ended tube extending through said body at right angles to the direction of said opening, a projecting threaded nipple of the same dimensions as said first-mentioned nipple provided at one end of said tube, and a projecting funnel provided at the other end of the tube.

2. The herein described attachment for the radiator of an automobile, comprising a ball shaped hollow body having an opening surrounded by a projecting threaded nipple adapted to engage a threaded hole in the radiator, an open-ended tube formed integral with said ball and extending therethrough at right angles to the direction of said opening, said tube projecting at both ends outside the hollow body, a projecting threaded nipple of the same dimensions as said first-mentioned nipple formed integral with the tube at one end thereof, and a projecting funnel formed integral with the tube at the other end thereof.

3. In testimony whereof I have signed my name.

JOHAN ANSHELM GRANSTEDT.
